UNITED STATES PATENT OFFICE.

ERICH OTTO, OF STETTIN-PODEJUCH, GERMANY.

FLYING MACHINE.

Application filed April 29, 1924. Serial No. 709,936.

To all whom it may concern:

Be it known that I, ERICH OTTO, a citizen of the German Republic, residing at Stettin-Podejuch, Post Sydowsaue, Germany, have 5 invented new and useful Improvements in Flying Machines, of which the following is a specification.

This invention relates to a flying machine of the kind provided with two pairs of carrying planes of which one pair is held in a rotatable mounting and adapted to be pitched to act as a lifting propeller while rotated together with the mounting, the other pair of planes being adapted to be set 10 in a vertical position to act as stability planes.

In a known machine of this kind, the propelling planes are connected by means of swinging frames, whereby the pitching 20 is effected, to another frame adapted to rotate about the main body of the machine, the stability planes being carried by the main body above the rotatable ones.

The object of the present invention is to 25 produce a machine of this kind which is of simple construction and which can be easily controlled, and the invention consists in arranging each pair of planes on horizontal, coaxial shafts about which the adjustment 30 takes place by means of suitable gears. The propelling planes are carried above the stability planes by a rotatable mast which surrounds the fuselage and which contains the gear whereby the planes are pitched.

Fig. 1 of the accompanying drawings 35 represents a side view of the machine, partly in section, and

Fig. 2, a cross-section of the same on the line 2—2 of Fig. 1.

The flying-machine is provided with two 40 pairs of carrying planes 1 and 4. The upper pair of planes is carried by a mast 3 which is rotatably held in the fuselage 2 by ball-bearings 5 and 6. There is a friction disc 7 secured to the lower end of the mast which 45 is engaged by a driving disc 7' arranged at right angles thereto. The disc 7' is slidably feathered on a shaft 9 which is coaxial with the crank shaft of the engine 8 and 50 which can be coupled thereto by means of a clutch 10 so that the mast and the planes carried by the same can be rotated by the motor. The ratio of transmission can be 55 regulated by an adjustment of the disc 7' across the face of the disc 7, and this is effected by means of a hand-wheel 15 con-

nected to a screw which controls the position of the disc by means of a fork 22, in known manner.

The planes 1 are held by independent 60 tubular shafts 12 which are rotatably held in the mast 3. The adjacent ends of the shafts are fitted with flanges 23 which are connected by links 11' to a rod 11, the latter being slidably arranged inside the mast 3 so 65 that it can be adjusted for positioning the planes 1. The links 11' operate at opposite sides of the axis of the flanges, as shown in Fig. 1, so as to turn the planes in opposite directions. The rod 11 is connected to a 70 grooved collar 24 which is slidably arranged on the mast 3 and which is controlled by a fork 25. The latter is adjustable by means of a screw-spindle 13 and a hand-wheel 14 for positioning the planes 1. 75

The lower pair of planes 4 is connected to a tubular shaft 16 which traverses the fuselage 2 and which is controlled by two trains of gear wheels 18', 19 and 19'. The wheels 18' mesh with toothed sectors 18 secured to 80 a shaft 26, and this shaft can be rotatively adjusted by means of an arm 27 connected to a hand-lever 17. This mechanism can be used for adjusting the planes 4 to any position between the vertical and horizontal. 85

The clutch 10 is operated by means of a hand-lever 28. A hand-lever 29 is used for operating a clutch 21 whereby the ordinary propellers 30 can be coupled to and disconnected from the engine shaft. When the 90 propeller is disconnected from the engine, it can be arrested by means of a brake 20 which is operated through the medium of a hand-lever 31.

For ordinary flying, the planes are set in 95 a more or less horizontal position, and the propeller 30 is coupled to the engine. For ascent and descent, the propeller 30 is disconnected and stopped, the mast 3 is coupled to the engine, and the planes 1 are set 100 at an angle to the horizontal in opposite directions so as to act as a lifting screw. At the same time the planes 4 are set in a vertical position, as shown dotted in Fig. 1, so 105 as to act as stabilizing plane. The speed of the lifting screw is regulated by an adjustment of the friction disc 7'.

I claim:

1. A flying machine of the character described comprising a fuselage, a rotatable 110 mast surmounting said fuselage, a pair of horizontal, coaxial shafts held rotatably by

2

said mast, carrying planes connected to said shafts, means for rotating the mast, means for pitching the planes about the shafts so that they will act as a lifting propeller when the mast is rotated, a pair of horizontal, coaxial shafts held rotatably in the fuselage, carrying planes connected to said latter shafts, and means for adjusting said latter shafts rotatively for varying the 10 angular position of their planes.

2. A flying machine of the character described comprising a fuselage, a rotatable, hollow mast surmounting said fuselage, two horizontal, coaxial shafts held rotatably 15 by said mast, carrying planes connected to said shafts, a rod arranged to slide within the mast, a crank mechanism connecting said rod to the shafts so that the latter can be turned thereby for pitching the planes 20 to act as a lifting propeller, means for imparting rotation to the mast, two horizontal, coaxial shafts held rotatably in the fuselage, carrying planes connected to said lat-

ter shafts, and means for adjusting said latter shafts rotatively for varying the 25 angular position of their planes.

3. A flying machine of the character described comprising a fuselage, a rotatable, hollow mast surmounting said fuselage, two horizontal, coaxial shafts held rotatably 30 by said mast, carrying planes connected to said shafts, a rod arranged to slide within the mast, a crank mechanism connecting said rod to the shafts so that the latter can be turned thereby for pitching the planes 35 to act as a lifting propeller, a driving shaft arranged at right angles to the mast, a friction gear adapted to transmit motion from the driving shaft to the mast at different speeds, a pair of horizontal, coaxial shafts 40 held rotatably in the fuselage, carrying planes connected to said latter shafts, and gears for turning said latter shafts for varying the angular position of their planes.

ERICH OTTO.
